UNITED STATES PATENT OFFICE.

WESLY M. CLINE, OF ROGERSVILLE, TENNESSEE.

CHURN.

SPECIFICATION forming part of Letters Patent No. 340,194, dated April 20, 1886.

Application filed August 17, 1885. Serial No. 174,587. (No model.)

To all whom it may concern:

Be it known that I, WESLY M. CLINE, a citizen of the United States, residing at Rogersville, in the county of Hawkins and State 5 of Tennessee, have invented certain new and useful Improvements in Churns; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 Figure 1 is a side elevation of the dasher-actuating mechanism and a diametrical section through the churn-body. Fig. 2 is a side view of the cover for the churn-body. Fig. 3 is a bottom view of the same. Fig. 4 20 is a vertical section taken through Fig. 1 in the course of dotted line x.

This invention relates to certain novel improvements in mechanism for rotating churn-dashers; and it consists in the combination and arrangement of devices hereinafter fully 25 described, and pointed out in the claim.

A designates the base of a goose-neck standard, B, vertically through the overhanging portion of which latter is a bearing for a 30 spindle, C. This spindle C has formed on its lower part an enlarged coupling-head, a, which is bored axially to receive the upper end of the dasher-rod D, which latter is held in its place in said enlargement by a removable coupling-pin, b. On the upper part of 35 the spindle, and sustained upon the top of the standard B, is a bevel-pinion, E, which is detachable from its spindle by removing a key-pin, c.

40 F designates a toothed segment, the teeth of which are adapted to engage with those of the pinion E. This toothed segment is free to vibrate about a removable bolt, p, which is applied to or formed on a fixed pendant, 45 B', on one side of the standard B. The said segment is provided with a lever-handle, G, of suitable length.

It will be observed that the spindle and its pinion, and also the toothed segment, can be 50 readily detached from the standard B, for the purpose of packing the churn and mechanism in a small space for transportation.

H designates the body of the churn, which is of the upwardly-tapered shape represented in the annexed drawings. This churn-body 55 is provided with a self-retaining removable cover, J, which is constructed as follows:

d designates a concavo-convex dish having a hole centrally through it surrounded by a flange, e. Surrounding this dish d, and rising 60 above its annular flange f, is a rim or guard, g. Below the flange f is an annular skirting or rim, g', which is adapted to fit tightly into the mouth of the churn-body and to retain the cover in its place without leakage. The 65 peculiarity of the said skirting is that it is crimped or corrugated, as shown at h, and the corrugations are oblique to the vertical axis of the cover. To easily apply or remove this cover it is given a slight rotary or screw 70 movement. It will thus be seen that the cover is so constructed that it will return back into the churn-box any milk which escapes through the central hole in the dish d, and also that this cover will be retained on the churn-body 75 without other fastening than is afforded by the crimps h.

The dasher K consists of vertical beveled blades i i, secured to the dash-rod by short radial bars j j, as shown in Fig. 1. 80

For the purpose of equalizing the oscillations of the dash-rod, and at the same time fanning a person while operating the churn, I employ a fan, L, the handle of which is inserted into a hole made through the spindle 85 C above the pinion E, and the edge k of which is received between two of the teeth of said pinion. The fan thus applied is held firmly in proper position to effect the objects stated.

Having described my invention, what I 90 claim as new, and desire to secure by Letters Patent, is—

The combination of the tapered churn-box, its dasher and dash-rod, and mechanism for actuating the latter, as described, with a cover, 95 J, having a concavo-convex dish, d, a rim, f, flanges e g, and a corrugated skirting or flange, g', as shown and described.

In testimony whereof I affix my signature in presence of two witnesses.

WESLY M. CLINE.
